ROLL-ON INDORSE INK WELL

Arthur M. Pasinski, Detroit, Mich., assignor to Burroughs Corporation, Detroit, Mich., a corporation of Michigan

Filed Apr. 5, 1961, Ser. No. 100,955

4 Claims. (Cl. 118—268)

This invention relates generally to ink applicators and particularly to a cartridge type ink applicator.

In the past, it has been proposed to provide ink applicators of a character having an ink container, or well from which a wick projecting externally of the container applies the ink by contact to an inking roller for ultimate application to printing elements. One of the objections to such devices is ink leakage by capillary action during storage of the devices, which leakage becomes more active when the pressure in the container increases with accompanying increase in ambient temperature. This not only causes a loss of ink, but also renders the ink stained containers objectionable to handle. To overcome this condition, it has been proposed to provide a cap over the exposed end of the wick and seal it to the container. However, such caps and their application to containers are expensive and the successful sealing of them to the container is very difficult, particularly where a broad wick is required.

Accordingly, it is an object of the invention to provide an improved cartridge type ink applicator in which the above mentioned objections are obviated.

Another object of the invention is to provide an improved cartridge type ink applicator in which the above mentioned leakage problem is solved without need of sealing the wick outlet of the ink container.

Another object of the invention is to provide an improved cartridge type ink applicator in which the ink is separated from the wick by a pressurized inflatable capsule, puncturable when desired to effect contact between the ink and wick.

Other objects of the invention will become apparent from the following description, taken in connection with the accompanying drawings in which:

FIG. 1 is an end elevation of my ink cartridge shown in association with ink transfer rollers;

FIG. 2 is a plan view partly broken away and in section of the ink cartridge;

FIG. 3 is a horizontal sectional view partly in elevation and taken along the line 3—3 of FIG. 1;

FIG. 4 is a vertical cross sectional view taken along the line 4—4 of FIG. 2;

FIG. 5 is a plane view of a cover of the ink cartridge;

FIG. 6 is a perspective view of the ink cartridge;

FIG. 7 is an end view of the ink cartridge with the cover removed;

FIG. 8 is a cross sectional view similar to FIG. 4, showing a modification;

FIG. 9 is a sectional view taken longitudinally of the modified ink cartridge along the line 9—9 of FIG. 8, and

FIG. 10 is a perspective view of the wick of the ink cartridge.

Referring to the drawings by characters of reference and first to FIGS. 1 to 8, the ink applicator shown comprises, in general, an ink cartridge or container 10 and a wick 12. The wick 12 extends out of the container through an outlet 14 and, among other uses, may be employed to apply ink to a metal transfer roller 16 in contact with a distribution roller 18 for applying ink to one or more printing wheels 20, as illustrated in FIG. 1.

In order to provide an ink cartridge from which ink cannot leak during storage of the cartridge and yet one which can be readily placed in use, I provide within the

2

container 10 a puncturable capsule 22 containing the ink so as to separate the ink from the wick 12. That is, the wick 12 is within the container 10, but without the ink capsule 22. The capsule 22 may be made of any suitable material that may be easily fractured, such as a frangible thin glass wall structure or plastic material capsule. However, I prefer to use an expansible-contractable inflatable capsule of the structural character of toy rubber balloons, but preferably made of a higher quality of latex with a thin strong wall and a filler neck 24 (see FIG. 8).

Any suitable container may be used, the present container 10 being box-like in construction having a bottom wall 24, side walls 25 and 26, end walls 28 and 30 and a top wall 32. Preferably the container 10 is made of a plastic material or thermo-setting resin of sufficient degree of transparency to allow visual inspection of the quantity of ink remaining therein. The top wall 32 of the cartridge 10 is made separately from the cartridge proper, as a cover, and is cemented to the upper edges of side walls 25, 26, and end walls 28, 30 after the wick 12 and ink capsule 22 are placed within the container. Any suitable cement, such as any of the well-known resin cements, may be employed to secure and seal the top wall 32 to the upper edges of the container side and end wall. The top wall 32 is provided with a hole partially therethrough leaving a thin frangible or puncturable vane 31.

The wick 12 is preferably T-shaped having a stem or leg portion 34 extending along the container bottom wall 22 and then upwardly along the side wall 26 to the top wall 32 where the cross portion 36 of the T-shaped wick is held in the outlet 14, as shown in FIG. 4. In the edge of top wall 32 and adjacent the side wall 26 of the container 10 there is provided a recess 38 to receive the upper end portion 36 of the wick. Projecting upwardly from the top wall 32 and extending along the recessed edge thereof is a wick retainer member or flange 40 and on the other side of the wick there is provided an upstanding wick back-up member 42 which is preferably formed as an extension of the cartridge side wall 26. The back-up member 42 fits snugly into the recess 38 and with the retainer member 40 form a wick restricting passage, the wick being tightly clamped between the retainer member 40 and the back-up member 42. By making the wick T-shaped the amount of ink supplied to the wick cross portion 36 is controlled to avoid the application of an excess of ink, and I further reduce the amount of ink applied to roller 16 by having only end tap portions 44 of the wick for contact with roller 16.

The back-up member 42 terminates just below the upper end of the wick 12 and gives support to the otherwise flexible wick to keep the wick tab portions 44 in contact with the periphery of roller 16. The back-up member 42 terminates at its opposite ends inwardly of the cartridge end walls 26, 28, respectively, and fits snugly between the ends, as at 46 of the wick restricting passage.

Integral with the recessed edge 38 of the top wall 32 there is a pair of horizontally spaced locators or pins 48 which extend respectively through a pair of apertures 50 provided in the wick 12 whereby to locate the wick both horizontally and vertically and hold the wick against accidental displacement in any direction.

In constructing the ink applicator, the capsule 22 is filled with the desired quantity of ink and is internally pressurized to tension the wall of the capsule, the purpose being to utilize the tension to effect a tearing of the capsule wall when punctured so as to enlarge the rupture and thus insure ink flow to the wick 12. An inexpensive method of tensioning the capsule wall is to fill the capsule 22 with ink with the capsule supported only at its filler neck such that the weight of the ink distends the capsule wall, and then tie off the capsule neck 24 close to the body of the ink to hold the capsule wall tensioned. If

desired, a common knot may be tied in the filler neck or the capsule 22 may be otherwise sealed against leakage. Another way to pressurize the capsule 22 would be to partially inflate it with air or other gas. After tensioning the wall of the capsule 22, the capsule is placed in the container 10 and assumes approximately the shape shown in FIG. 9, due to an optimum supply of ink, the shape of the container 10, and tension of the wall of the capsule causing the upper curved surface of the capsule to project somewhat above the edges of the container. However, on applying and clamping the container top wall 32 in place, the ink in the capsule 22 is displaced into the upper corners of the container 10, as shown in FIG. 4, with the upper surface of the capsule 22 against the underside of the cover and overlying the puncturable vane 31. Thus, a sharp pointed tool may be inserted through the vane 31 into and puncture the latex capsule 22 whereupon the tension force of the capsule wall will act to tear the same at the puncture point and release the ink for flow to the wick 12.

The modification of FIGS. 2 and 8 is similar to the previously described ink cartridge and, therefore, like characters of reference, designate like parts. The modification differs from the previously described cartridge in that the stem portion 34 of the T-shaped wick 12 is disposed between the upper rounded surface of the capsule and the underside of the container top wall 32 so that the wick will be adjacent to the point of the puncture and receive ink immediately following the puncturing of the capsule. In addition, the wick portion 34 overlies the puncturable vane 31 and prevents discharge of ink through the vane hole at the time that the puncture is made.

What is claimed is:

1. In an ink applicator, a rigid outer container having a puncturable top wall and an ink outlet, an inner capsule of ink and puncturable through the top wall of said outer container, said capsule having a contractable tensioned wall acting to enlarge any puncture made in the capsule, and a wick between the top wall of said outer container 35 and a puncturable vane 31.

40

and said capsule and having an end portion projecting from said outlet and held by the tensioned wall of said capsule against the underside of said top wall.

5 2. In an ink applicator, a rigid outer container having a puncturable wall and an ink outlet, a wick within said container and having an end portion passing through and projecting out of the outlet of said container, and a puncturable ink containing inflatable capsule within said container, said capsule internally pressurized to aid flow of the ink into said container upon puncturing the capsule.

10 3. In an ink applicator, a container having a wall including a relatively thin frangible portion and having an ink outlet, an internally pressurized inflatable capsule of ink within said container and puncturable by an instrument insertable through said frangible portion, and a wick having one end projecting from said outlet and positioned between said frangible portion and said capsule to prevent discharge of ink through the frangible portion when the capsule is punctured and held thereagainst by said pressurized capsule.

15 4. In an ink applicator, a rigid outer container having an open top and an attachable cover therefor, said cover having a frangible portion and a cutout area forming an ink outlet, an inflated, flexible capsule of ink within said container and puncturable through said frangible portion of said cover, said inflated capsule extending through said open top before said cover is attached and displaced by the attachment of said cover to increase the pressure thereon, and a wick lying between said capsule and an inner surface of said container and having an end portion projecting externally of said container through said outlet.
